DESIGN FOR A BINOCULAR OR THE LIKE

William F. Peck, Snyder, N. Y., assignor to
Spencer Lens Company, Buffalo, N. Y., a cor-
poration of New York

Application September 24, 1941, Serial No. 103,463

Term of patent 14 years

To all whom it may concern:

Be it known that I, William F. Peck, a citizen
of the United States of America, residing at
Snyder, in the county of Erie and State of New
York, have invented a new, original, and ornamental
Design for a Binocular or the like, of
which the following is a specification, reference
being made to the accompanying drawings, forming
a part thereof.

Fig. 1 is a perspective view of binocular em-
bodying my design;

Fig. 2 is a bottom plan view thereof;

Fig. 3 is an end view showing the eyepiece end
thereof;

Fig. 4 is an end view showing the objective end
thereof; and

Fig. 5 is a side view thereof.

I claim:

The ornamental design for a binocular or the
like, substantially as shown.

WILLIAM F. PECK.
